CLAIM

The ornamental design for a latching single cam connector, as shown and described.

DESCRIPTION

FIG. 1 is a top front and right side perspective view of a latching single cam connector showing my new design;

FIG. 2 is a top plan view thereof;

FIG. 3 is a front elevation view thereof;

FIG. 4 is a left side elevation view thereof, the right side elevation view is a mirror image thereof;

FIG. 5 is a rear elevation view thereof; and,

FIG. 6 is a bottom plan view thereof.

The broken line showing of the environment is for illustrative purposes only and forms no part of the claimed design.

It is certified that error appears in the above-identified patent and that said Letters Patent is hereby corrected as shown below:

The title page showing and illustrative figure, should be deleted and substitute therefore
the attached title page.

The sheets of drawings consisting of figures 1-4 should be deleted to appear as per
attached figures 1-4.

Signed and Sealed this

Fourteenth Day of September, 2010

David J. Kappos
Director of the United States Patent and Trademark Office
